UNITED STATES PATENT OFFICE

152,838

DESIGN FOR A BEAM COMPASS

Alexander F. Stephen, Des Plaines, Ill., assignor
to American Molded Products Co., Chicago, Ill.,
a corporation of Illinois

Application August 14, 1947, Serial No. 140,876

Term of patent 14 years

(Cl. D52—1)

To all whom it may concern:

Be it known that I, Alexander F. Stephen, a citizen of the United States, and a resident of Des Plaines, in the county of Cook and State of Illinois, have invented a certain new, original, and ornamental Design for a Beam Compass, of which the following is a specification, reference being had to the accompanying drawing, forming a part thereof:

Figure 1 is a side elevational view of a beam compass showing my new design;

Figure 2 is a top plan view;

Figures 3 and 4 are rear and front end views respectively;

Figure 5 is a bottom plan view; and

Figure 6 is a perspective view showing the position of the parts in an operative position of use.

I claim:

The ornamental design for a beam compass, substantially as shown.

ALEXANDER F. STEPHEN.
